UNITED STATES PATENT OFFICE.

MARIUS ANTOINE, OF PARIS, FRANCE, ASSIGNOR TO THE FIRM OF ETABLISSEMENTS BESNARD, MARIS & ANTOINE, OF PARIS, FRANCE.

LAMP OR LANTERN.

1,356,898.

Specification of Letters Patent. Patented Oct. 26, 1920.

Application filed March 5, 1920. Serial No. 363,597.

To all whom it may concern:

Be it known that I, MARIUS ANTOINE, citizen of the French Republic, residing at 60 Boulevard Beaumarchais, Paris, France, have invented certain new and useful Improvements in Lamps or Lanterns, of which the following is a specification.

This invention relates to an arrangement for mounting petrol or similar lamps in portable lanterns or in those intended for the lighting of vehicles the object of this arrangement being to enable the flame to be regulated by imparting a rotary movement to the lamp without opening the lantern.

15 The accompanying drawing given by way of example represents one of the methods of carrying out the invention.

Figure 1 is a side elevation of a carriage lamp shown partly in section.

20 Fig. 2 is a front view.

Fig. 3 is a plan view of the mounting arrangement.

Fig. 4 is a sectional detail view on a larger scale.

25 The body of the lantern 1 has in its base an orifice furnished with a seating or holder 2 intended to receive the petrol lamp 3 which rests on the seating by its rim 3^a. The lamp is taken out and put in through 30 the interior of the lantern.

This lamp can be furnished with a burner of the petrol light type in which the height of the wick is regulated by the rotation of a porcelain or metal wick adjuster.

35 A resilient fixing for the lamp illustrated by way of example comprises two parallel metal arms 4, 4^a made of wire and hingedly connected at 5 with the lantern 1.

At their opposite ends the arms 4, 4^a 40 carry a pivoted hook 6. Two transverse distance plates 7, 7^a Fig. 3 are secured to the arms near the ends and keep them at the proper distances apart. Near the middle the arms are bent to form coils 4^b, 4^c.

45 When the lamp is put in place the two arms are turned down, the two coils thereof bearing against a flange member 8 on the wick adjuster and the hook 6 is fixed in a staple or lug 9 which is soldered on to the 50 body of the lantern.

In these conditions in consequence of the resilient pressure of the two arms the lamp is held in place on its seat and cannot be displaced by the vibrations or shaking of the vehicle. Moreover the two coils 4^b, 4^c, exer-

cise a rather powerful vertical pressure on the flange 8 of the wick adjuster so that this cannot rotate. The result is that if the reservoir 3 of the lamp which protrudes through the bottom of the lantern be turned 60 by hand, thus turning the lamp body, the wick is caused to move up or down that is to say the flame is regulated in the same manner as if the lamp reservoir or body, were fixed and the wick adjuster were turned in 65 the interior of the lantern.

Thus by means of this simple and practical arrangement the flame can be regulated in petrol lamps, without the necessity of opening the doors of the lantern at the risk 70 of extinguishing the flame.

The burner shown in the drawing has in its upper part a head 10 which insures the steadiness of the flame in motor carriage lanterns.

Likewise the arrangement of the two arms may be modified according to the shape of the lantern without departing from the principle of the invention so long as the essential functions of keeping the lamp in 80 place and preventing the rotation of the wick adjuster when the lamp body is rotated are satisfactorily performed.

It is obvious that other methods and other forms of construction could be adopted and 85 that the details of construction could also be varied in many ways. On the other hand the various constituent elements of this invention could be replaced by others acting in the same way or giving the same result. 90

I claim:

The combination with a lantern of a lamp body mounted in said lantern to turn therein, means for adjusting the wick in said lamp body, said means having a flanged member, and means for fixedly holding the wick adjusting means inside the lantern to permit the flame to be regulated by the turning of the lamp body, the said holding means comprising two resilient arms hinged to the interior of the lantern and capable of applying pressure to said flanged member of the wick adjusting means, the said arms serving at the same time to keep the lamp body on its seat, and a fastening capable of 100 being engaged in a lug soldered onto the body of the lantern.

In testimony whereof I have affixed my signature.

MARIUS ANTOINE.
